J. A. DEWIRE

CASTING

Filed July 24, 1922

John A. Dewire,
Inventor,
Delos G. Haynes,
Attorney

UNITED STATES PATENT OFFICE.

JOHN A. DEWIRE, OF CHICAGO, ILLINOIS, ASSIGNOR TO MILLER & PARDEE, INC., OF CHICAGO, ILLINOIS, A CORPORATION OF ILLINOIS.

CASTING.

Application filed July 24, 1922. Serial No. 577,009.

To all whom it may concern:

Be it known that I, JOHN A. DEWIRE, a citizen of the United States, and a resident of Chicago, county of Cook, State of Illinois, have invented an Improvement in Castings, of which the following is a specification.

This invention relates to casting, and with regard to certain more specific features, to die casting.

10 Among the several objects of the invention may be noted the provision of a simple and effective construction of a casting; and the provision of an inexpensive and reliable method of making castings having elements 15 rotatably mounted therein. Other objects will be in part obvious and in part pointed out hereinafter.

20 The invention accordingly comprises the features of construction, steps and sequence 20 of steps, combinations of elements and arrangements of parts, which are exemplified in the description hereinafter in connection with the accompanying drawings, and the scope of the application of which will be 25 indicated in the following claims.

25 In the accompanying drawings, in which is illustrated somewhat diagrammatically one of various possible embodiments of the invention,

30 Figure 1 is a face view of a rotatable element, having a ferrule thereon;

Fig. 2 is a fragmentary section on the line 2—2 thereof, on an enlarged scale;

35 Fig. 3 is a similar view of Fig. 1 showing the element as it appears after the casting operation;

Fig. 4 is a fragmentary section on the line 4—4 of Fig. 3, on an enlarged scale;

40 Fig. 5 is a plan of a die element, taken on the line 5—5 of Fig. 6; and

Fig. 6 is a section on the line 6—6 of Fig. 5.

45 Similar reference characters indicate corresponding parts throughout the several views of the drawings.

Referring now more particularly to Figs. 1 to 4 of the accompanying drawings, there is illustrated at 1 an element such as a bail adapted to be rotatably mounted within a casting 3 (Figs. 3-4).

50 I have found that if the rotatable element is merely placed in the die blocks and the metal cast around it, it is difficult or im-

possible to avoid waste, due to spoiled castings.

55 In order to reduce or eliminate this waste I provide the rotatable element with a metallic ferrule 5 (Figs. 1 and 2) prior to the casting operation. The ferrule is long enough so that when the article is placed in the die blocks (Figs. 5 and 6) the ferrule extends entirely across the surface for the cast metal.

60 The ferrule has a diameter slightly larger than the outside diameter of the rotatable member, providing enough clearance so that the ferrule is rotatable with respect to said member.

65 The ferrule is of sufficient mechanical strength to withstand the compression encountered during the die casting operation.

70 The die blocks are shown conventionally in Figs. 5 and 6 as comprising two blocks or halves 9, 10, recessed to provide space for the cast metal around the bail and ferrule. 75 Spaces are also provided at 13 for the entrance of the metal from a suitable source (not shown). A slight clearance is provided at 15 between the two blocks, to permit escape of air. The blocks are shown as 80 adapted for the simultaneous casting of two articles. Obviously they could be adapted for the casting of one article only, or of more than two articles.

85 The complete article is shown in Figs. 3 and 4.

From the above it will be seen that the several objects of the invention are attained and other advantageous results achieved.

90 As many modifications of the embodiment above illustrated might be made without departing from the spirit or scope of the present invention, it is intended that the above description and accompanying drawings and claims shall be interpreted as illustrative and not in a limiting sense.

I claim:

1. The method of die casting an article having a movable element therein, which comprises surrounding the movable element 100 with a member movable with respect to said element and adapted to resist the compression encountered during die casting, and then casting the article around said member.

105 2. The method of die casting an article

having a movable element therein, which comprises surrounding the movable element, at all points liable to come in contact with the cast metal, with a member spaced from said element and adapted to resist the compression encountered during die casting, and then casting the article around said member.

3. The method of die casting an article 10 having an element rotatable therein, which comprises surrounding the element, at all points liable to come in contact with the cast metal, with a ferrule adapted to resist the compression encountered during die 15 casting, and then casting the article around said member.

4. A die casting having a movable element therein separated from the cast metal by a member movable with respect to said 20 element and adapted to withstand the compression encountered during die casting.

5. A die casting having a movable element therein separated from the cast metal by a member spaced from said element and 25 adapted to withstand the compression encountered during die casting.

6. A die casting having an element rotatable therein separated from the cast

metal by a ferrule adapted to withstand the compression encountered during die 30 casting.

7. In combination, an article adapted to be inserted in a die casting and to be movable therein, and a member surrounding it at points liable to come in contact with the cast metal, and movable with respect to the article and adapted to withstand the compression encountered during casting.

8. In combination, an article adapted to be inserted in a die casting and to be movable therein, and a member surrounding it at all points liable to come in contact with the cast metal, and spaced from the article and adapted to withstand the compression 40 encountered during casting. 45

9. In combination, an article adapted to be inserted in a die casting and to be rotatable therein, and a ferrule surrounding it at all points liable to come in contact with the cast metal and adapted to withstand the compression encountered during casting. 50

In testimony whereof, I have signed my name to this specification this 20th day of July, 1922.

JOHN A. DEWIRE.
